UNITED STATES PATENT OFFICE.

ADOLPH RUBIN, OF ST. LOUIS, MISSOURI, ASSIGNOR TO SIEBER PRODUCTS MFG. CO., OF ST. LOUIS, MISSOURI, A CORPORATION OF MISSOURI.

LOOSE-LEAF BINDER.

1,334,406.

Specification of Letters Patent. Patented Mar. 23, 1920.

Application filed February 26, 1919. Serial No. 279,279.

To all whom it may concern:

Be it known that I, ADOLPH RUBIN, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same.

10 This invention relates to loose leaf binders of the kind that are provided with tapes, bands or cords of flexible material for retaining the loose leaves in position, and particularly to binders of the type that are used 15 for ledgers and other large books containing a great many loose leaves and which comprise a back made of metal or other rigid material.

The loose leaf binders of the particular 20 type referred to which have heretofore been devised cannot be opened out as flat as a flexible back binder, owing to the fact that the rigid metal back holds the tapes so taut when the binder is open that the intermediate leaves cannot move upwardly sufficiently 25 to cause the rear edges of the leaves of the book to assume the shape of an arc. Such binders also necessitate the use of loose leaves provided with relatively deep or wide 30 rear edge margins, in view of the fact that the portions of the leaves in proximity to the binding tapes, particularly the intermediate leaves, are so disposed when the binder is open that it is extremely difficult to write 35 on said portions.

One object of my invention is to provide a practicable loose leaf binder for ledgers and other large books containing a great many leaves, which is equipped with a back 40 that has sufficient rigidity to hold the book in shape and which is so constructed that the leaves can open out flat or in substantially the same manner as the leaves of a binder provided with a back formed of fabric or other flexible material.

Another object is to provide a loose leaf binder having a back formed of metal or other suitable rigid material and constructed in such a manner that the binder can be successfully used with loose leaves provided 50 with relatively narrow or shallow rear edge margins.

And still another object is to provide a

loose leaf binder in which the leaf clamping members can move relatively to the back 55 when the binder is opened into a position in which they do not form bends in the leaves or interfere with the leaves lying flat. Other objects and desirable features of my invention will be hereinafter pointed out. 60

To this end I have devised a loose leaf binder comprising tapes or bands of flexible material that pass transversely through the leaves and a back composed of a plurality of sections or members formed of metal or 65 other suitable rigid material and pivotally connected together in such a manner that the back as an entirety is capable of flexing or bending sufficiently when the binder is opened to slacken the tapes enough to allow 70 the leaves to assume substantially the same position as the leaves of a binder provided with a flexible back formed of fabric, leather or similar material. The leaves are held tightly clamped together by leaf clamping 75 members carried by the back of the binder, and while it is immaterial, so far as my broad idea is concerned, how the leaf clamping members are mounted on the back, I prefer to mount said leaf clamping members in 80 such a manner that they can move relatively to the back when the binder is opened into such a position that they do not form bends in the leaves or prevent the leaves from lying flat or assuming a substantially horizontal 85 position.

Figure 1 of the drawings is an end elevational view of a book equipped with a loose leaf binder constructed in accordance with my invention, showing the book closed. 90

Fig. 2 is a similar view, showing the book open.

Fig. 3 is a similar view, illustrating another form of my invention.

Fig. 4 is a perspective view of the book 95 illustrated in Fig. 3; and

Fig. 5 is an end elevational view, illustrating still another form of my invention.

My improved loose leaf binder comprises two leaf clamping members A and A' between which the loose leaves B of a book are arranged, a plurality of tapes or bands C of flexible material that pass transversely through slots in the leaves B, and thus retain the leaves in operative position, and a 100 winding shaft D for drawing the tapes C 105

taut so as to cause the leaf clamping members A and A' to clamp the rear edge portions of the leaves together, said winding shaft being normally locked so as to prevent it from turning in a direction to release or slacken the tapes C. The particular construction of the winding shaft and the locking mechanism for said shaft form no part of my present invention and may be 10 of any preferred form or construction.

Instead of providing the binder with a rigid back that holds the leaf clamping members in the same spaced relation, both when the binder is open and closed, I have 15 provided my improved binder with a back that is composed of a plurality of rigid sections which are hinged together or pivotally connected together in such a manner that the back as an entirety has sufficient 20 flexibility to permit the leaf clamping members to move toward each other when the book is opened, and thus slacken the tapes sufficiently to permit the leaves to assume such a position that the rear edges of the 25 leaves form an arc. In other words, the back of my improved binder has sufficient rigidity and strength to hold the book in shape, even when the book is composed of a large number of leaves, but it permits the 30 intermediate leaves to move upwardly and spread out substantially flat in practically the same manner as the leaves of a binder provided with a flexible back formed of fabric, leather or other similar material. This 35 characteristic of my binder is illustrated clearly in Figs. 1 and 2, wherein it will be noted that the leaf clamping members are closer together when the binder is open than when the binder is closed.

40 In the form of my invention illustrated in Fig. 1 the back of the binder is composed of two sections E and E' that are hinged together or pivotally connected together by a pintle 1 that extends longitudinally of 45 the back between coöperating ears or bearings 2 on the adjacent edges of the sections E and E', said bearings being staggered and arranged in interlocking engagement with each other in substantially the same manner as the pintle receiving portions on the 50 leaves of a hinge. The sections E and E' are provided at their free edges with flanges 3, and the coyers F and F' of the binder are pivotally connected to said flanges 3 by pintles 4 that pass through coöperating bearing portions 5 and 5^a on the covers and on the flanges 3, respectively.

60 The leaf clamping members A and A' are substantially angle shaped in cross section, so as to provide a portion on each of said leaf clamping members that laps over the rear edges of the leaves arranged adjacent the covers, and said leaf clamping members are preferably connected to the 65 sections E and E' of the back in such a

manner that they can turn into such a position when the binder is opened that the portions of said leaf clamping members which bear against the outside leaves will extend in the same general direction in which the 70 leaves extend, and thus not form bends in the leaves or prevent the leaves from lying flat. One convenient way of mounting the leaf clamping members A and A' is to provide said members with bearing portions 75 5^b through which the pintles 4 pass, thus causing said members to be hinged to or rockably mounted on the back of the binder. When the binder is opened the portions of the leaf clamping members that bear 8 against the rear edges of the leaves tend to exert upward pressure on the leaves, and thus cause them to spread out flat.

It is immaterial how many sections are used to form the back of the binder, and in 85 instances where the binder is designed for use with books composed of an exceedingly large number of loose leaves, it is desirable to construct the back of four sections, as shown in Fig. 3, namely, two outer sections 90 E and E' and two intermediate sections E² and E³, all of said sections being hinged together or pivotally connected together in such a manner that the back can flex or bend sufficiently when the binder is opened 95 to shorten the distance between the leaf clamping members, and thus slacken the tapes enough to allow the leaves to assume such a position that the rear edges of same 100 form an arc.

In Fig. 5 I have illustrated still another form of my invention, wherein the back of the book is composed of one intermediate section E⁴ and two side sections E and E', all of which are pivotally connected or 105 hinged together.

Having thus described my invention, what I claim and desire to secure by Letters Patent, is:

1. A loose leaf binder, comprising leaf 110 clamping members, tapes or bands of flexible material that pass transversely through the leaves and cause said clamping members to hold the leaves clamped tightly together, and a back supporting said leaf-clamping members and composed of a plurality of sections of rigid material pivotally connected together by a hinge that extends longitudinally of the back intermediate the side edges of same. 115

2. A loose leaf binder, comprising a back formed of rigid material and provided intermediate its side edges with a longitudinally-disposed hinge, flanges on said back, leaf clamping members pivotally connected 125 to said flanges, and a tape or band of flexible material that passes transversely through the leaves and causes said leaf clamping members to clamp the leaves tightly together. 130

3. A loose leaf binder, comprising a back composed of a plurality of rigid sections pivotally connected together intermediate the side edges of the back leaf clamping members pivotally mounted on said back, and a tape or band of flexible material that passes transversely through the leaves and causes said leaf clamping members to hold the leaves tightly clamped. 30
- 5 4. A loose leaf binder, comprising a back composed of a plurality of rigid sections pivotally connected together, and leaf clamping members hinged to said back. 35
- 10 5. A loose leaf binder, comprising a back composed of a plurality of rigid sections hinged together intermediate the longitudinal side edges of the back, covers hinged to said back, pivotally mounted leaf clamping members carried by the back, and a flexible tape or band that passes transversely through the leaves and causes the leaf clamping members to hold the leaves clamped tightly together. 40
- 15 20 6. A loose leaf binder, comprising a back composed of a plurality of rigid sections pivotally connected together, covers, pintles that pass through coöperating bearings on 45
- 25 said back and covers for hinging the covers to the back, and leaf clamping members rockably mounted on said pintles. 50
7. A loose leaf binder provided with a back composed of two side sections formed of rigid material, leaf-clamping members carried by said side sections and means arranged between said side sections and pivotally connected to same for holding them in spaced relation when the binder is closed and for permitting them to move toward each other when the binder is opened. 55
8. A loose leaf binder provided with a back formed of rigid material and composed of two side sections and a plurality of intermediate sections, all of which are pivotally connected together by hinges extending longitudinally of the back, and leaf-clamping members carried by said side sections. 60
9. A loose leaf binder, comprising a back formed of rigid material, and leaf clamping members pivotally connected to said back and provided with portions that bear against the rear edges of some of the leaves. 65

ADOLPH RUBIN.
